UNITED STATES PATENT OFFICE.

WILLIAM A. DOBSON, OF BRIDGEPORT, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed May 15, 1923. Serial No. 639,068.

To all whom it may concern:

Be it known that I, WILLIAM A. DOBSON, a citizen of the United States, residing in Bridgeport, in the county of Fairfield and State of Connecticut, have invented certain new and useful Improvements in Typewriting Machines, of which the following is a specification.

This invention relates to a type-action for typewriting machines, and particularly for machines of the portable class. Such type-actions must be compact, and the weight of the machine must be reduced to a minimum. It is also preferable that the action be simple and composed of few parts, and the machine-work must be reduced to a minimum so that the cost of manufacture may be reduced and so allow the machine to be sold at a comparatively low price.

One object of this invention is to produce a condensed and yet highly efficient type-action, in which the various parts are so placed with relation to one another that a small, compact and easily portable machine is secured.

Another object of this invention is to so mount the various parts of the mechanism as to cause their longitudinal axes to fall on approximately parallel lines, which will eliminate the binding of the parts when set in motion and, by so doing, will decrease the pressure necessary to operate them.

Another object of this invention is to eliminate all superfluous parts of the type-action, to increase the efficiency and smooth action of those which are retained and to so simplify the design of the latter as to appreciably reduce the cost of their manufacture. This invention results in a type-action that is extremely simple and efficient in operation, is practical and long-lived, produces work that compares very favorably with the work which can be turned out on a standard-sized machine, is light and compact and therefore easily portable, and can be manufactured at a reasonable cost and therefore sold at a comparatively low price.

The type-bars of this type-action are short and are arranged in a type-bar segment that is preferably taken from a disk of comparatively small diameter. The arc on which

the type-bar pivot-rod lies is therefore one of short radius, which reduces the space required to accommodate the type-bars and therefore aids in reducing the size of the machine.

The axes of the slots which accommodate the type-bars lie in planes which radiate from a common center approximately coincidental with the printing point, which brings them more nearly parallel to one another than would be the case if a lower center were used. The result is a group of type-bars, any two of which present practically parallel surfaces to one another. This arrangement allows ample space between the type-bars to accommodate the necessary actuating mechanism without danger of the various parts interfering with one another in action.

The type-bar segment is preferably inclined rearwardly from the perpendicular at an angle of approximately 10° , which allows the type-bars to be swung through a greater arc, and which makes it possible to place the platen in back of the type-bar segment and lower down in the machine than would be permissible if the segment were placed in the vertical position. This lowering of the platen is not only very desirable as a means of reducing the height of the machine, but also for the reason that the printing line can be raised, so that, as in this invention, it will appear above a horizontal plane taken through the longitudinal axis, and nearer to the top of the platen, where it is more visible than would be the case if it appeared lower down.

When at rest, all of the type-bars lie in a conical plane that in this instance forms an angle of approximately 95° with the surface of the backwardly-inclined type-bar segment, thus causing the type-bars to spread outwardly a trifle, as they recede from the segment, and yet leave them not too far from a horizontal position. The lowermost type-bars are thus brought close to the key-levers, which further reduces the height of the machine. Each type-bar has a projecting ear that extends rearwardly and downwardly from the type-bar and affords a means for swinging the type-bar on its pivot.

The fulcrums of the key-levers, while they might be arranged in parallel alignment with the key-levers themselves, are in this instance grouped together closely on an centrally-disposed transverse fulcrum-plate near the rear of the machine, and radiate toward the front of the machine where they are spread out to the full width required for a standard keyboard. The use of a relatively short straight fulcrum-plate is preferred because it fulfills all practical requirements and affords substantial vacant spaces on each side of the bank of key-levers to accommodate the other necessary mechanism of the machine without adding appreciably to its width.

The fulcrum-plate in this instance is provided with pins or projections along its top edge above the key-levers, and coiled springs are stretched between the individual key-levers and their corresponding pins in a manner to hold the key-levers in place upon the fulcrum-plate and also to cause the return of the key-levers to normal after the pressure of the typist's fingers has been removed. The key-levers have fingers depending from their lower edges, which are bendable to the proper height to actuate a universal bar to which may be attached the ribbon-vibrating and carriage-release mechanisms.

The type-bar-actuating mechanism, which connects the key-levers to the type-bars, preferably takes the form of a series of links and bell-cranks.

The bell-cranks in this instance are mounted in a bridge that is preferably curved on an arc having for its center the point to which the radial portions of the key-levers would substantially converge if they were extended backwardly beyond the fulcrum-plate. The axes of the slots formed in the bridge to accommodate these bell-cranks are, in the presence instance, along lines which radiate from this point, and these lines are preferably so drawn that the bell-cranks will fall to the inside of the key-levers, i. e., on the right and left hand sides of the key-levers on the left and right hand sides, respectively, of the type-action, beginning at a line drawn through the center of the action from front to back. This arrangement of the bell-cranks will, of course, bring their flat surfaces parallel to the flat surfaces of the key-levers which operate them, which is desirable for the purpose of reducing friction or binding between these two parts of the mechanism. The forwardly-extending arms of the bell-cranks have slots to receive projecting pins fastened on the key-levers. The sliding connection thereby effected allows the key-levers to rock the bell-cranks on their pivots as the former descend under pressure of the typist's fingers. The arc on which the bell-crank pivot-rod

lies is of relatively slight curvature, and, due to the shorter radius of the type-bar segment, the last few bell-cranks at the right and left hand sides of the type-action are somewhat beyond the outermost type-bars. 70

The universal bar, in this instance, is arcuate in a horizontal plane, and preferably parallel with the bridge supporting the bell-cranks, so that a uniform balance is obtained between the points of engagement 75 of the radial key-levers with the universal bar and the bell-cranks mounted on the bridge member.

The links, in this instance, are in the form of short, stiff wires, and have hooks formed 80 on their opposite ends. When assembled, the hooks of each link connect the rearwardly-projecting ear of a type-bar with the upwardly-extending arm of the corresponding bell-crank. 85

It is preferable to arrange these links in a conical plane just below and substantially parallel to the conical plane in which the type-bars normally lie, and to have the link for each type-bar lie as nearly in line with the latter as possible. This arrangement permits a link to oscillate a type-bar about its pivot by giving it a straight pull, and reduces to the minimum any tendency for the type-bar to bind or twist in its slot. To 90 avoid interfering contact during movement of the links, the links are preferably bent intermediate their ends. 95

To further aid in accomplishing this object, the upwardly-extending arms of those bell-cranks which lie beyond the limits of the outside type-bars on both the right and left sides of the type-action are in this instance bent inwardly until they meet the ends of the parallel links which are to be fastened to them. The manner in which the type-bars are connected to the bell-cranks by means of the links is clearly illustrated in the drawings. 100

Other features and advantages will hereinafter appear. 110

In the accompanying drawings,

Figure 1 is a plan view of the type-action, showing the relative positions of the various parts, and especially the manner in which their longitudinal axes are disposed along lines that radiate from a common point. 115

Figure 2 is a partial, front, sectional view of the type-action, taken substantially on the line 2-2 of Figure 4, and shows how the axes of those working parts above the bell-crank pivots lie approximately in straight lines radiating downwardly from a common point taken on a vertical bisecting line of the action. 120

Figure 3 is a perspective view of the curved bridge in which the bell-crank pivot-rod is held, and shows the construction of the arcuate slotted passage, in which the pivot-rod is seated. 125

Figure 4 is a longitudinal, sectional view of a typewriter, taken approximately on the center line of the type-action, showing the relative positions of the various parts 5 of the type-action when the type-bars are at rest.

Figure 5 is a side view of the center, stiffening member which binds most of the various transverse members of the type-action 10 into a rigid whole.

Figure 6 is a view of three of the type-bar-actuating links as they appear when in their normal positions.

Figure 7 is a view of the same three type-bar-actuating links, shown in Figure 6, in the positions assumed when the middle link has oscillated its type-bar, and shows the manner in which interference with the other mechanism is avoided during operation by 20 slightly bending the links.

The typewriting machine in this instance includes a frame 10, composed of side bars 11 and 12 fastened together in front by a cross-bar 13 and in the rear by a cross-bar 14, 25 and supported in a false frame or shell 15 having a front cross-member 16, a top cross-member 17, a rear cross-member 18 and side members 19 and 20.

Feet 21, preferably made of resilient material, such as rubber, are fastened to the frame 10 and support the typewriter upon a base or other support. Fastened between the cross-members 17 and 18, and lying on the center line of the frame 10, is a stiffening-bar 22 that is also fastened to the cross-member 14. Ears 23 and 24 project toward opposite sides from the top of the bar 22 and support an angle-brace 25 that, in turn, supports a type-bar segment 26. The segment 40 26 is further supported, on each side, by members 27 and 28 which are bent down and fastened to the side members 11 and 12.

Mounted in the center of the segment 26 is a type-guide 29. Type-bars 30, which 45 preferably carry type-heads 31 having three types 32, are mounted in slots 34 on a pivot-rod 35 and have rearwardly-projecting ears 33 normally below the pivot-rod 35. The type-bars 30 in this instance have stops 36, 50 which serve to regulate the force of the blow delivered by the types 32 against the platen, and projections or guides 37 which co-operate with the type-guide 29 in guiding the types to the printing point, and which also serve 55 as stops to prevent the types on the head of an advancing type-bar from striking against the type-head of a receding bar, and from becoming damaged thereby. The type-bar segment 26 is preferably inclined rearwardly 60 from the perpendicular at an angle of approximately 10 degrees, which allows the type-bars 30 to be swung through a greater arc and which makes it possible to lower the platen in back of the segment 26, thus 65 reducing the height of the machine. This low-

ering of the platen also has a tendency to raise the printing line to a higher position on the front surface of the platen and above the horizontal plane in which the longitudinal axis of the platen lies, which makes it 70 more visible than it would be if it lay directly in that horizontal plane.

When the type-bars 30 are lying in normal position, the type-heads 31 rest upon a type-bar rest, rail or basket 38 overlaid 75 with suitable cushioning material, such as felt, and supported upon the central stiffening-bar 22 and also at its ends on the cross-members 39 which run from the members 27 and 28 to the cross-member 17. It will be 80 noticed that the entire group of type-bars 30 occupies comparatively little space in the machine, and that the highest type-bar, when it is at rest, is not much higher than the highest bank of keys in the keyboard. 85

Fastened to the rear cross-member 14, to the right and left respectively of the center of the type-action, are brackets 40 and 41 which support a transverse key-lever fulcrum-plate 42 preferably slotted, as at 43, 90 to receive the fulcrum-ends of key-levers 44, and the fulcrum plate 42 has projections or pins 45 formed along its top edge to which coil-springs 46 are fastened. The other ends of the coil-springs 46 are fastened to the 95 key-levers 44 and act to return the latter to their normal positions after being released from the pressure of the typist's fingers. The key-levers 44 radiate from the fulcrum-plate 42 towards the front of the machine, 100 where they pass through slots 47 in the front cross-member 13, which also acts as a comb-plate. When they reach this point they are spread out sufficiently to form a standard width key-bar. 105

By observing Figure 1, it will be noted that, if the key-levers 44 were continued rearwardly beyond the fulcrum-plate 42, their longitudinal axes would find a common center some distance to the rear of the machine. The key-levers 44 are provided with fingers 48 on their lower edges which are adjustable in height and which operate a curved universal bar 49 attached at its ends to a transverse rock-shaft 50 also supported by the brackets 40 and 41. The universal bar 49 carries a lever 51 which operates the ribbon-vibrating mechanism and a lever 52 which operates the carriage-release mechanism, a part of which is shown at 53. The universal bar 49 is preferably curved in the form of an arc in a horizontal plane, and is returnable to normal, after each depression, by means of fingers 54, 115 preferably made of spring steel. Near their forward ends, the key-levers 44 are provided with downwardly-depending ears 55 furnished with pins or cams 56, the purpose of which will hereinafter be more fully described. 120

Lying beneath the key-levers 44, and fastened to the side members 11 and 12, is a bar or bridge member 57, preferably curved on an arc struck from the same center to which the radial axes of the key-levers converge, and parallel with the universal bar 49. The bridge-member 57 is preferably made in two parts, an upper part 58 having a curved groove 59, and a lower part 60 having a complementary curved groove 61. The two parts 58 and 60 are suitably fastened together, as by the pins 62, and in this position the grooves 59 and 61 produce a continuous passage or hole through which a bell-crank pivot-rod 63 is insertable. The parts 58 and 60 constituting the bridge-member 57 are preferably provided with slots 64, which extend transversely through the grooves 59, and the axes of which are approximately parallel to, and to the right and left of, the key-levers 44 on the left and right hand sides, respectively, of the type-action, see Figure 1. These slots cause the parts 58 and 60 having the complementary grooves 59 and 61 to produce, in effect, a plurality of separate, uniform, arcuately-aligned apertures, and the walls of the apertures thus produced provide the support for the bell-crank pivot-rod 63. Bell-cranks 65 are mounted in the slots 64 on the pivot-rod 63, so that the legs 66 will extend upwardly between the key-levers 44 and the other legs 67 will project toward the front of the machine and lie adjacent the depending ears 55 to which they will be parallel.

Slots 68, to engage the pins 56, are preferably formed in the legs 67. The legs 67 also have openings 69 to receive the hooked ends 70 of links 71, the other hooked ends 72 of which are fastened into similar openings 73 in the backwardly-extending ears 33 of the type-bars 30.

Referring to Figure 1, it will be seen that the group of key-levers 44 and their accompanying bell-cranks 65 extend over a somewhat wider area than that occupied by the type-bars 30 and their actuating links 71. By bending in the tops of the legs 66 toward the center, it will be seen that the longitudinal axes of the type-bars 30, actuating links 71, bell-cranks 65 and key-levers 44 of the type-action units, throughout the entire action, are brought into substantial parallelism in radiating planes, which will prevent, to a great extent, any binding of parts or side pull when a type-action unit is placed in operation. This alone, however, would not accomplish the desired result, as the direction of motion of the bell-cranks, while in about the same plane as the type-bars at the center of the type-action, takes place in intersecting planes at increasing angles to the type-bars toward the outer sides of the action. The rocking of the bell-crank imparts to the link

a forward movement of undulatory character, which, at the commencement of the type stroke, includes a downward component of the rear end of the link and an upward component of the front end. When the link 70 pivot-point 69 of the leg 66 reaches the highest point in its arc of travel the link pivot-point 73 of the ear 33 will be at its lowest point. Toward the end of the type stroke the movement of the link-ends undergoes a reversal of direction, so that the rearward link-end moves upward with the ear 33 and the forward link-end moves downward with the bell-crank. So far as the outermost type-action units are concerned the printing takes place before any stretching of the link occurs to exert side pull on the bell-crank, but actually the bends in the legs 66 of the outermost bell-cranks 65 are so located that any deflection, due to forcible depression of the keys, is easily overcome by the universal action of the connections between the links 71 and the legs 67 which permits a slight turning movement of the bell-crank arms within the looped ends of the links and a slight turning of the links in a horizontal plane about the pivot-points of the ears 33.

It will be observed, in Figures 1 and 2, that the planes, on which the axes of the various parts of the mechanism lie, are arranged in two groups, one radiating from a vertical line located some distance in back of the machine, and the second radiating downwardly from an approximately horizontal line drawn through the center of the disk from which the type-bar segment is taken, and that the bends in the legs 66 occur at the points of bi-section for these planes. By arranging the mechanism in this manner, no one type-action unit will be harder to operate than any other, and the same finger pressure applied to any key of the keyboard will produce a like result. Because the bend in a leg 66 causes its top to move in an arc almost tangent to the normal cumbent plane of the top of an immediately succeeding leg, its actuating link tends to move closer and closer to the next succeeding leg-tip toward either the right or left of the machine as that leg is moved forwardly, in the manner illustrated in Figure 7. The links 71 which lie near the extreme right and left hand edges of the group are bent in their middles to correct this tendency to interfere with the adjacent leg 66, as shown in Figures 6 and 7, and, although this tendency is not so marked in those links 71 which lie toward the center of the type-action, where the bends in the legs 66 are less acute, these central links 71 are also preferably bent to preserve a uniform length of link throughout the entire group.

It will be appreciated that when a key-lever 44 is depressed its pin 56 will travel

toward the bottom of the cam slot 68 in the bell-crank 65 which is adjacent, thus producing the double result of increasing the speed of the type-bar 30 and of reducing the leverage power of the leg 67, and, by doing so, placing an increasing check on the force of the finger blow. The long leverage of the leg 67 at the beginning of the motion tends to make starting easy, and shortening 10 the leverage of the leg 67 as the motion progresses tends to make stopping easy. This acceleration of the speed of the type-bar 30 toward the platen at the beginning of the type stroke is reversed when it recedes from 15 the platen. In other words, on the advance, the type-bar 30 starts slowly and gradually increases its speed, while on the return it starts quickly and gradually slows up its speed. The speed with which the 20 type-bar 30 leaves the platen facilitates the clearing of the printing point for the arrival of the next type-bar 30, and thus enables the typist to attain greater writing speed. This pin and cam slot arrangement 25 permits of a light touch on the keys, easy stopping of the type-bars 30 at the end of their travel, and an equally easy stopping of the type-bars upon their return to rest; the former cushioning the blow and slowing 30 the finger movement, and the latter exerting a brake action by lengthening the leverage in favor of the key weight; and a more rapid manipulation of the key-levers 35 when typing. It will be seen from the foregoing description that the mechanism here described is simple and efficient in operation, is extremely compact, occupies but little space, is sturdy and substantial in construction, and may be built at a moderate 40 cost.

Whenever it is desired to detach one of the bell-cranks, the rod 63 is pushed through the passage in the curved bridge by means of a follower, which permits a bell-crank 45 to be removed without disturbing the location of others.

Variations may be resorted to within the scope of the invention, and portions of the improvements may be used without others.

Having thus described my invention, I 50 claim:

1. The combination in a typewriting machine including a frame and a platen, of a type-action including a plurality of radial 55 key-levers, a type-bar segment of short radius, a plurality of type-bars pivoted in said segment and normally cumbent in a substantially conical plane with the lowermost type-bars in practically a horizontal plane, a plurality of bell-cranks pivoted in an arc in a horizontal plane of greater radius than 60 said segment and of lesser extent than the outermost key-levers, said bell-cranks having upwardly-extending arms bent inwardly 65 at progressively sharper angles as they approach the outer limits of the type-action, operative connections between said type-bars and said bell-cranks, and means co-operative between said key-levers and said bell-cranks for actuating said bell-cranks. 70

2. The combination in a typewriting machine including a frame and a platen, of a type-action including a plurality of radial key-levers, a type-bar segment of short radius, a plurality of type-bars pivoted in said segment and normally cumbent in a substantially conical plane with the lowermost type-bars in practically a horizontal plane, a plurality of bell-cranks pivoted in an arc in a horizontal plane of greater radius than said 75 segment and of lesser extent than the outermost key-levers, a plurality of links connecting said type-bars and said bell-cranks, the connections of said links to said bell-cranks being such as to afford a slight turning movement of the links in practically a horizontal plane toward the end of the type-stroke, and means co-operative between said key-levers and said bell-cranks for actuating 80 said bell-cranks. 85

3. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter. 95

4. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, said fulcrum-plate having a plurality of slots and a plurality of pins formed along its lower and upper edges respectively, spring-members coactive between said key-levers and said pins normally tending to retain said key-levers in said slots in inoperative position, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a plurality 100

115

120

125

130

of bell-cranks pivoted in said bridge in arcuate alignment and within lesser limits than the outermost key-levers, operative connections between said type-bars and said bell-cranks, and means co-operative between said key-levers and said bell-cranks for actuating the latter.

5. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a plurality of bell-cranks mounted directly in slots in said bridge or a unitary pivot-rod and within lesser limits than the outermost key-levers, operative connections between said type-bars and said bell-cranks, and means co-operative between said key-levers and said bell-cranks for actuating the latter.

6. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a plurality of bell-cranks mounted directly in slots in said bridge on a unitary pivot-rod and within lesser limits than the outermost key-levers, operative connections between said type-bars and said bell-cranks, each of said key-levers having a depending ear and a pin projecting from said ear, and corresponding bell-cranks each having an arm slotted to receive said pin.

7. The combination in a typewriting machine including a frame and a platen, of a type-action including a plurality of radial key-levers, depending fingers on said radial key-levers, a flat universal bar curved in a horizontal plane, said universal bar being directly engageable with said depending fingers to actuate ribbon-vibrating and letter-feeding mechanism, a type-bar segment of short radius, a plurality of type-bars pivoted in said segment and normally cumbent in a substantially conical plane with the lowermost type-bars in practically a horizontal plane, a plurality of bell-cranks

pivoted in an arc in a horizontal plane of greater radius than said segment and of lesser extent than the outermost key-levers, said bell-cranks having upwardly-extending arms bent inwardly at progressively sharper angles as they approach the outer limits of the type-action, operative connections between said type-bars and said bell-cranks, and means co-operative between said key-levers and said bell-cranks for actuating said bell-cranks.

8. The combination in a typewriting machine including a frame and a platen, of a type-action including a plurality of radial key-levers, depending fingers on said radial key-levers, a flat universal bar curved in a horizontal plane, said universal bar being directly engageable with said depending fingers to actuate ribbon-vibrating and letter-feeding mechanism, spring-members engageable with the under side of said universal bar for urging the bar to its inoperative position, a type-bar segment of short radius, a plurality of type-bars pivoted in said segment and normally cumbent in a substantially conical plane with the lowermost type-bars in practically a horizontal plane, a plurality of bell-cranks pivoted in an arc in a horizontal plane of greater radius than said segment and of lesser extent than the outermost key-levers, a plurality of links connecting said type-bars and said bell-cranks, the connections of said links to said bell-cranks being such as to afford a slight turning movement of the links in practically a horizontal plane toward the end of the type-stroke, and means co-operative between said key-levers and said bell-cranks for actuating said bell-cranks.

9. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a flat universal bar located at the rear of said bridge, said universal bar being curved in a horizontal plane and directly engageable by said key-levers, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter.

10. The combination in a typewriting machine including a frame and a platen, of

- a type-action including a transverse fulcrum-plate at the rear of said frame, a transverse comb-plate at the front of said frame and a plurality of key-levers mounted between said fulcrum and comb plates, said fulcrum-plate having a plurality of slots and a plurality of pins formed along its lower and upper edges respectively, spring-members coactive between said key-levers and said pins normally tending to retain said key-levers in said slots in inoperative position, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a flat universal bar located at the rear of said bridge, said universal bar being curved in a horizontal plane practically parallel with said transverse curved bridge, fingers depending from said key-levers and directly engageable with said universal bar, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter.
11. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a flat universal bar located at the rear of said bridge, said universal bar being curved in a horizontal plane practically parallel with said transverse curved bridge, fingers depending from said key-levers and directly engageable with said universal bar, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter.
12. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a flat universal bar located at the rear of said bridge, said universal bar being curved in a horizontal plane practically parallel with said transverse curved bridge, fingers depending from said key-levers and directly engageable with said universal bar, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter.
13. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, said fulcrum-plate having a plurality of slots and a plurality of pins formed along its lower and upper edges respectively, spring-members coactive between said key-levers and said pins normally tending to retain said key-levers in said slots in inoperative position, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a flat universal bar located at the rear of said bridge, said universal bar being curved in a horizontal plane practically parallel with said transverse curved bridge, fingers depending from said key-levers and directly engageable with said universal bar, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter.
14. The combination in a typewriting machine including a frame and a platen, of a type-action including a transverse fulcrum-plate at the rear of said frame, a transverse comb-plate at the front of said frame and a plurality of key-levers mounted between said fulcrum and comb plates, said fulcrum-plate having a plurality of slots and a plurality of pins formed along its lower and upper edges respectively, spring-members coactive between said key-levers and said pins normally tending to retain said key-levers in said slots in inoperative position, a type-bar segment of short radius, a plurality of type-bars pivoted in said segment and normally cumbent in a substantially conical plane with the lowermost type-bars in practically a horizontal plane, a transverse curved bridge between said fulcrum-plate and said comb-plate, a flat universal bar located at the rear of said bridge, said universal bar being curved in a horizontal plane practically parallel with said transverse curved bridge, fingers depending from said key-levers and directly engageable with said universal bar, a plurality of bell-cranks pivoted in said bridge in arcuate alignment and within lesser limits than the outermost key-levers, operative connections between said type-bars and said bell-cranks, and means co-operative between said key-levers and said bell-cranks for actuating the latter.

said fulcrum and comb plates, a type-bar segment of short radius, a plurality of type-bars pivoted in said segment and normally cumbent in a substantially conical plane 5 with the lowermost type-bars in practically a horizontal plane, a transverse curved bridge between said fulcrum-plate and said comb-plate, a flat universal bar practically parallel with said bridge, said universal bar 10 being curved in a horizontal plane and of lesser extent than the distance between the outermost key-levers, and actuated by said key-levers to operate ribbon-vibrating and letter-feeding mechanism, said transverse 15 curved bridge occupying lesser limits than the distance between the outermost key-levers and being formed of two interlocking parts, both of said parts having complementary transverse slots, means for securing 20 said parts together to form a unitary segment, a plurality of bell-cranks mounted directly in the slots in said bridge on a unitary pivot-rod and within lesser limits than the outermost key-levers, operative connections 25 between said type-bars and said bell-cranks, and means co-operative between said key-levers and said bell-cranks for actuating the latter.

15. The combination in a typewriting machine including a frame and a platen, of a type-action including a transverse fulcrum-plate at the rear of said frame, a transverse comb-plate at the front of said frame and a plurality of key-levers mounted between said 30 fulcrum and comb plates, said fulcrum-plate having a plurality of slots and a plurality of pins formed along its lower and upper edges respectively, spring-members co-active between said key-levers and said pins normally tending to retain said key-levers in 35 said slots in inoperative position, a type-bar segment of short radius, a plurality of type-bars pivoted in said segment and normally cumbent in a substantially conical plane 40 with the lowermost type-bars in practically a horizontal plane, a transverse bridge between said fulcrum-plate and said comb-plate, said bridge including two interlocking parts of lesser transverse extent than the 45 distance between the outermost key-levers, each of said parts having a complementary groove extending longitudinally of the bridge to afford a circular passage therein, both of said parts having a plurality of 50 aligned complementary slots, a bell-crank pivot-rod inseparable in said circular passage and a plurality of bell-cranks supported on said pivot-rod within said slots, means for securing 55 said bridge-parts together to form a unitary segment, fingers depending from said key-levers, a flat universal bar curved in a horizontal plane at the rear of said bridge and directly engageable by said fingers to actuate ribbon-vibrating and letter-feeding mechanism, spring-members en- 60

gageable with the under side of said universal bar urging the bar to its inoperative position, a plurality of links between said type-bars and said bell-cranks, each of said key-levers having a depending ear and a pin 70 projecting from said ear, and corresponding bell-cranks each having an arm slotted to receive said pin, to actuate said bell-cranks and hence the type-bars.

16. In a type-action for a typewriting machine, the combination of a plurality of key-levers radiating from a central point in the rear, toward the front of said type-action, where they form a standard keyboard, a plurality of type-bars arranged on a conical 75 surface of less width than the bank of said key-levers, and close above them, a plurality of links each having one of its ends attached to one of said type-bars, and its other end radiating forwardly in a conical plane, and 80 parallel to said type-bar, a transverse curved bridge below said key-levers, and a plurality of bell-cranks mounted in said bridge, each having one leg extending upwardly between said key-levers, and being bent inwardly to 85 receive the free end of one of said links, and the other leg extending forwardly to engage one of said key-levers, the lines of motion each lying in two planes, the change in direction occurring at the bends in said upwardly-extending legs, and at sharper angles 90 in the outermost type-action units.

17. In a type-action for a typewriting machine, the combination of a plurality of key-levers having downwardly-depending ears 100 having pins, and radiating from a central point in the rear, toward the front of said type-action, where they form a standard keyboard, a plurality of type-bars arranged in a conical plane of less width than the bank of said key-levers, and close above them, a plurality of links each having one of its ends attached to one of said type-bars, and its other end radiating forwardly in a 105 conical plane, and parallel to said type-bar, a transverse curved bridge below said key-levers, and a plurality of bell-cranks mounted in said bridge, each having one leg extending upwardly between said key-levers, and being bent inwardly to receive the free 110 end of one of said links, and the other leg provided with a slot, and extending forwardly to be engaged by the pin of one of said key-levers, the lines of motion each lying in two planes, the change in direction 115 occurring at the bends in said upwardly-extending legs, and at sharper angles in the outermost type-action units.

18. In a type-action for a typewriting machine, the combination of a plurality of key-levers having downwardly-depending ears 125 having pins, and radiating from a central point in the rear, toward the front of said action, where they form a standard keyboard, a plurality of type-bars having rear- 130

- wardly-extending ears, and arranged in a backwardly-inclined segment, and extending forwardly in a conical plane of less width than the bank of said key-levers, and close above them, a plurality of links each having one of its ends attached to said rearwardly-extending ear of one of said type-bars, and its other end radiating forwardly in a conical plane, and parallel to said type-bars, a transverse curved bridge below said key-levers, and a plurality of bell-crank 5 70
10 mounted in said bridge, each having one leg extending upwardly between said key-levers, and being bent inwardly to receive the free 15 end of one of said links, and the other leg provided with a slot, and extending forwardly to engage said pin on one of said key-levers, the lines of motion each lying in two planes, the change in direction occurring 20 75
25 ring at the bends in said upwardly-extending legs, and at sharper angles in the outermost type-action units.
19. In a type-action for a typewriting machine, the combination of a plurality of key-levers having downwardly-depending ears having pins, and radiating from a central point in the rear, toward the front of said action, where they form a standard keyboard, a plurality of type-bars having rearwardly-extending ears, and arranged in a backwardly-inclined segment, and extending forwardly in a conical plane of less width than the bank of said key-levers, and close above them, a plurality of links each having one of its ends attached to said rearwardly-extending ear of one of said type-bars, and its other end radiating forwardly in a conical plane, and parallel to said type-bar, a curved horizontal transverse bridge below 30 80
35 said key-levers, and provided with a plurality of radial slots, and a plurality of bell-crank 40 mounted in said slots in said bridge, each having one leg extending upwardly between said key-levers, and being bent inwardly to receive the free end of one of said links, and the other leg provided with a slot, and extending forwardly to engage said pin on one of said key-levers, the lines of motion each lying in two planes, the change 45 85
50 in direction occurring at the bends in said upwardly-extending legs, and at sharper angles in the outermost type-action units.
20. In a type-action for typewriting machines, in combination with a plurality of radial key-levers, bell-crank, links and type-bars, and a curved, transverse bridge for supporting said bell-crank, having a plurality of slots arranged on radial lines drawn parallel to the longitudinal axes of 55 90
60 said radial key-levers, and so positioned that, when said bell-crank are inserted therein, the broad surfaces of said bell-crank will lie parallel to the flat surfaces of said key-levers, said bell-crank being pivoted on a curved pivot-rod mounted in said transverse bridge below said key-levers, one leg of each of said bell-crank extending upwardly past said key-levers, said upwardly-extending legs being bent inwardly and out of parallelism with said key-levers, and being inclined backwardly at an angle of approximately ten degrees from the perpendicular.
21. In a type-action for typewriting machines, in combination with a plurality of radial key-levers, bell-crank, links and type-bars, and a curved, transverse bridge for supporting said bell-crank, having a plurality of slots arranged on radial lines drawn parallel to the longitudinal axes of 65 95
70 said radial key-levers, and so positioned that, when said bell-crank are inserted therein, the broad surfaces of said bell-crank will lie parallel to the flat surfaces of said key-levers, said bell-crank being pivoted on a curved pivot-rod mounted in said transverse bridge.
22. In a type-action for typewriting machines, in combination with a plurality of radial key-levers, bell-crank, links and type-bars, and a curved, transverse bridge for supporting said bell-crank, having a plurality of slots arranged on radial lines drawn parallel to the longitudinal axes of 75 100
80 said radial key-levers, and so positioned that, when said bell-crank are inserted therein, the broad surfaces of said bell-crank will lie parallel to the flat surfaces of said key-levers, said bridge being in two parts, and said bell-crank being pivoted on a curved pivot-rod mounted in said transverse bridge between said parts.
23. In a type-action for typewriting machines, in combination with a plurality of radial key-levers, bell-crank, links and type-bars, and a curved, transverse bridge for supporting said bell-crank, having a plurality of slots arranged on radial lines drawn parallel to the longitudinal axes of 85 105
90 said radial key-levers, and so positioned that, when said bell-crank are inserted therein, the broad surfaces of said bell-crank will lie parallel to the flat surfaces of said key-levers, said bridge being in two parts, each part having a curved groove formed therein, and said bell-crank being pivoted on a curved pivot-rod mounted in the curved hole formed by said groove when said parts are joined.
24. In a type-action for a typewriting machine, the combination of a plurality of key-levers radiating from a common point in the rear of said action in a horizontal plane, a transverse bridge below said key-levers, and a plurality of bell-crank to be operated by said key-levers, and mounted in said transverse bridge between, and parallel to, said key-levers, one leg of each of said bell-crank extending upwardly past said key-levers, said upwardly-extending legs being bent inwardly and out of parallelism with said key-levers, and being inclined backwardly at an angle of approximately ten degrees from the perpendicular.
25. In a type-action for a typewriting machine, the combination of a plurality of key-levers having downwardly-depending ears furnished with pins, and radiating from a common point in the rear of said action in a

- horizontal plane, a curved, transverse bridge below said key-levers, and a plurality of bell-cranks mounted in said transverse bridge between, and parallel to, said key-levers, one leg of each of said bell-cranks extending upwardly past said key-levers, said upwardly-extending legs being bent inwardly out of parallelism with said key-levers, and being inclined backwardly at an angle of approximately ten degrees from the perpendicular, the other legs of said bell-cranks having slots formed therein, and extending forwardly to engage said pins.
26. In a type-action for a typewriting machine, the combination of a curved, transverse bridge having radial slots formed therein, a plurality of bell-cranks mounted in said slots, a plurality of radial key-levers mounted alternately between said bell-cranks, said key-levers having downwardly-depend ing ears with pins formed thereon to engage slots in the forwardly-extending legs of said bell-cranks, the other legs of said bell-cranks extending upwardly and being bent toward the center at the intersection of an arc inclined rearwardly from the perpendicular, their ends lying on another arc of smaller radius within said inclined arc, a plurality of type-bars lying on a concave, conical surface parallel to, and a short distance above, said inner arc, and a plurality of links lying in a similar concave, conical surface between said type-bars and said key-levers, and connecting said upwardly-extending legs to said type-bars.
27. In a type-action for a typewriting machine, the combination of a curved, transverse bridge having radial slots formed therein, a plurality of bell-cranks mounted in said slots, a plurality of radial key-levers mounted alternately between said bell-cranks, said key-levers having downwardly-depend ing ears with pins formed thereon to engage slots in the forwardly-extending legs of said bell-cranks, the other legs of said bell-cranks extending upwardly and being bent toward the center at the intersection of an arc inclined rearwardly from the perpendicular, their ends lying on another arc of smaller radius within said inclined arc, a plurality of type-bars lying in a concave, conical plane parallel to, and a short distance above, said inner arc, and a plurality of links lying in a similar concave, conical plane between said type-bars and said key-levers, and connecting said upwardly-extending legs to said type-bars, the lines of motion of said bell-crank legs of the type-action units being in two planes, one of which intersects the other at the bends in said upwardly-extending legs, said key-levers terminating at their forward ends in a standard keyboard having three banks of keys, a like depression of a key of any bank producing a like motion in its connected type-bar.
28. In a type-action for a typewriting machine, the combination of a curved, transverse bridge having radial slots formed therein, a plurality of bell-cranks mounted in said slots, a plurality of radial key-levers mounted alternately between said bell-cranks, said key-levers having downwardly-depend ing ears with pins formed thereon to engage slots in the forwardly-extending legs of said bell-cranks, the other legs of said bell-cranks extending upwardly and being bent toward the center at the intersection of an arc inclined rearwardly from the perpendicular, their ends lying on another arc of smaller radius within said inclined arc, a plurality of type-bars lying in a concave, conical plane parallel to, and a short distance above, said inner arc, and a plurality of links lying in a similar concave, conical plane between said type-bars and said key-levers, and connecting said upwardly-extending legs to said type-bars, the lines of motion of said bell-crank legs of the type-action units being in two planes, one of which intersects the other at the bends in said upwardly-extending legs, said key-levers terminating at their forward ends in a standard keyboard having three banks of keys, a like depression of a key of any bank producing a like motion in its connected type-bar.
29. A typewriter-key-action including a type-bar segment, a plurality of type-bars pivotally mounted therein, a plurality of key-levers, and a plurality of bell-cranks and links operatively connecting said key-levers and said type-bars, and a transverse bridge for supporting said bell-cranks, said bridge being curved in a horizontal plane so that the effective portion thereof occupies lesser limits than the distance between the outermost key-levers, and having a plurality of slots aligned with said key-levers, said bell-cranks being pivoted on a curved pivot-rod within said transverse bridge, said links being bent intermediate their ends, and each of said bell-cranks having one bent portion.

WILLIAM A. DOBSON.
